(57) **CLAIM**

The ornamental design for a container panel as shown and described.

DESCRIPTION

FIG. 1 is a perspective view of a container panel showing the subject design;

FIG. 2 is a front view of the container panel shown in FIG. 1;

FIG. 3 is a top view of the container panel shown in FIG. 1; FIG. 4 is a side view of the container panel shown in FIG. 1; and,

FIG. 5 is a perspective view of the container panel shown in FIG. 1, showing the environment of a multiple container panel assembly.

The broken lines indicated that the article is of indefinite length. The stippled lines portions form no part of the claimed design.
